UNITED STATES PATENT OFFICE.

JOSEPH GOMEZ, OF JACKSONVILLE, ILLINOIS.

CHAIR-TRUCK.

1,304,677.

Specification of Letters Patent. Patented May 27, 1919.

Application filed May 21, 1918. Serial No. 235,810.

To all whom it may concern:

Be it known that I, JOSEPH GOMEZ, a citizen of the United States, residing at Jacksonville, in the county of Morgan and State 5 of Illinois, have invented certain new and useful Improvements in Chair-Trucks, of which the following is a specification.

This invention relates to trucks, and has for its object the provision of a truck onto 10 which rocking or other chairs may be bodily placed whereby invalids or others occupying the chairs may be readily transported from place to place about a hospital, sanatorium or the like, with the utmost ease to the operator and with the minimum discomfort to the occupant of the chair.

An important object is the provision of a truck of this character which may be quickly and easily adjusted to accommodate chairs 15 of widely varying dimensions.

A further object is the provision of a truck of this character which is provided with an extensible footrest, which is adjustable with the truck to conform to the adjustments 20 in the width thereof, which is extensible to project to a greater or less extent beyond the front of the chair, which may be adjusted to different heights, and which is revolubly supported, these various adjustments 25 affording the maximum comfort and convenience to the occupant of the chair.

An additional object is the provision of a device of this character which will be comparatively simple and inexpensive in manufacture, efficient and durable in service, and a general improvement of the art.

With the above and other objects and advantages in view, the invention consists in the details of construction to be hereinafter 30 more fully described and claimed, and illustrated in the accompanying drawings, in which:—

Figure 1 is a plan view of the device,

Fig. 2 is a side elevation showing a rocking chair thereon in dotted lines,

Figs. 3, 4, and 5 are detail sectional views on the lines 3—3, 4—4, and 5—5, respectively, of Fig. 1.

Fig. 6 is a bottom plan view of the foot 40 rest,

Fig. 7 is a detail perspective view,

Fig. 8 is a plan view of the device showing the straight chair supporting attachment, and

Fig. 9 is a sectional view therethrough.

Referring more particularly to the draw-

ings, the numeral 10 designates the supporting caster members of my device, as a whole. Each of these caster members includes a body 11 formed preferably as a casting including a disk-like platform 12 and spaced laterally extending ears 13. Revolubly mounted on the underside of each platform 12, as by a pivot bolt 14, is a yoke 15 carrying a wheel 16 which may preferably be 60 rubber tired. The confronting faces of the platforms and yokes are provided with circular grooves forming raceways in which are disposed balls 17 whereby friction between the parts will be reduced to the minimum. 70 Formed upon the top of each platform 12 is a diametrically extending rib 18 and an upwardly extending lug 19, the purpose of which will be hereinafter made apparent. It will be noted that the body 11 of each 75 caster is so formed as to provide an upwardly extending portion 20 spaced from the lug 19.

The rear casters, and also the forward ones, are connected by slidably adjustable 80 transverse bars indicated broadly by the numeral 21. Each of these bars is formed of two similar sections 22, preferably angular in cross-section, connected by guide loops 23 which are secured upon the ends of the sections and which embrace the other sections.

The forward casters are connected with the rear casters by means of channel bars 24 which have their ends pivoted between the pairs of ears 13 by means of pins or bolts 25. 90 The upper edges of the channel bars at their confronting open faces are provided with flanges 26 which are cut away adjacent the rear casters, as shown at 27, for a purpose to be described.

When the bars 21 are adjusted to the proper width, a rocking chair may be placed upon the device with its rockers resting upon the ribs 18 on the platforms 12 and confined between the lugs 19 and upward extensions 100 20, as clearly shown by dotted lines in Fig. 2. The device may then be easily rolled from place to place, as desired, the revolubility of the wheel carrying yokes 15 facilitating the free and easy movement of the chair and truck.

The foot rest portion of my device is indicated broadly by the numeral 28 and comprises a pair of slidably adjustable strips 29 of angle iron having connection with each 110 other by means of guide lugs 30. A right angular bracket 31 is pivoted upon the outer

end of each strip 29 by a bolt or pin 32. The foot engaging member proper consists of an adjustable lazy tongs or lattice formed of a plurality of strips 33 pivotally connected with one another as shown at 34 and arranged as a "lazy-tongs." The endmost strips 33 are pivotally connected with the brackets 31 by the pins or bolts 32, this construction permitting the lattice to elongate 10 automatically when the bars 29 are slidably adjusted. The foot rest is detachable from the truck but is associated therewith by means of arms 35 which are pivotally connected with the brackets 31 as shown at 36. 15 These arms are disposed within guide forks 37 on the bodies of the forward casters and have their free ends laterally offset as shown and provided with lugs 39 riding within the channel bars 24. The cut away portions 27 20 of the flanges 26 permit insertion of the offsets and lugs within the channel bars. After the arms 35 are thus associated with the bars 24 the engagement of the flanges 26 with the lugs 39 will prevent displacement 25 thereof. In this arrangement, the foot rest may be slid along to extend a greater or less extent beyond the front of the chair and truck to suit the convenience of the occupant of the chair. The foot rest proper is revolvable 30 with respect to the arms 35 by virtue of the pivots 36 so that it may accommodate itself to the user. It will be noted that when the foot rest 28 is projected forwardly it will automatically be elevated. The lattice 35 is, of course, elongated or contracted to agree with the adjustment of the bars 21.

In order that the device may be adapted for use in connection with straight chairs as well as rocking chairs, I provide the attachment illustrated in Figs. 8 and 9. This attachment consists of a bar 40 of material provided upon its lower side with transverse grooves 41 adapted to fit upon the ribs 18. Two of these bars are used, one upon each 45 side of the device. Each bar is provided upon its upper face at its forward end with a block 42 provided with a circular recess 43 for the reception of the front legs of a chair as shown in Fig. 9. Furthermore, each bar 50 40 is longitudinally grooved upon its upper face for retaining the rear legs of the chair.

From the foregoing description and a study of the drawings, it will be apparent that I have thus provided a truck whereby 55 either rocking chairs or straight chairs may be wheeled from place to place with the ut-

most ease and convenience, which is adjustable to fit chairs of widely varying dimensions and which is provided with an adjustable and extensible foot rest whereby the greatest degree of comfort will be afforded 60 the occupant of the chair.

It will, of course, be understood that I reserve the right to make such changes in the form, construction, and arrangement of 65 parts as will not depart from the spirit of the invention or the scope of the subjoined claims.

Having thus described my invention, I claim:

1. A chair truck comprising a plurality of caster members, extensible bars connecting the forward and rear casters in pairs, bars connecting said forward pairs of casters with the rear pairs, and a laterally extensible foot rest longitudinally slidably associated with said last named bars, said foot rest being extensible in conformity to the adjustment of said first named bars. 70

2. A chair truck comprising a plurality of 75 caster members each provided upon its outer edge with a retaining lug, extensible bars connecting the forward and rear casters in pairs, channel bars connecting said forward casters with said rear casters, guide lugs on the forward caster members, and an extensible laterally adjustable foot rest including arms slidably associated between said guide lugs and having their ends slidably engaged within said channel bars and a lazy tongs 80 lattice pivoted between the forward ends of 85 said arms. 90

3. A chair truck comprising forward and rear caster members, bars connecting the forward with the rear caster members, extensible bars connecting the forward and rear caster members, respectively, a pair of spaced guide lugs on each forward caster member, a pair of arms slidably connected with said first named bars and engaging said 95 guide lugs, brackets pivotally connected with the forward ends of said arms upon their confronting faces, an extensible rod secured to said brackets, and a lazy tongs lattice including a plurality of crossed diagonally 100 disposed strips pivotally connected at their ends and crossings and disposed upon said rod, the endmost strips being connected with 105 said rod. 105

In testimony whereof I hereto affix my 110 signature.

JOSEPH GOMEZ.
